(57) **CLAIM**

The ornamental design for a crimping tool, as shown and described.

DESCRIPTION

FIG. 1 is a perspective view of a crimping tool showing the design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a partial enlarged view of the circle marked with 8 in FIG. 7.

The broken lines shown in the drawings indicate portions of the crimping tool which form no part of the claimed design.
